UNITED STATES PATENT OFFICE.

HENRY J. WELSH, OF BOSTON, ASSIGNOR TO FRANCIS L. MAGUIRE, OF SOMERVILLE, MASSACHUSETTS.

DESIGN FOR A SODA-FOUNTAIN PLATE.

SPECIFICATION forming part of **Design No. 25,276**, dated **March 24, 1896**.

Application filed October 16, 1895. Serial No. 565,914. Term of patent 14 years.

To all whom it may concern:

Be it known that I, HENRY J. WELSH, of Boston, in the county of Suffolk and State of Massachusetts, have invented and produced 5 a new and original Design for Front-Plate Heads for Sirup-Tanks for Soda-Water and Similar Fountains, of which the following is a specification, reference being had to the accompanying drawing, showing my new design in whole and in part.

The leading feature of my design consists in a front plate shaped and ornamented as herein set forth.

In the drawing, A is the oval center block 15 with its longest axis vertical, and A' is a surrounding rectangular framing beveled outwardly and rearwardly on its faces a, a', a² and a³. At the corner of the framing rays a⁴ project toward the oval center block and 20 fill the corners of the framing. The margin of the oval center block is ornamented with a chain of alternating small beads a⁵ and elongated beads a⁶. Above the oval center block and its framing is an elongated name-plate B, 25 the name-space b of which is formed of curved lines b', terminating in scrolls b², one at each

end of the name-space, the greatest length of which is from side to side of the front plate taken as a whole. The name-space b is surrounded by rectangular framing b³, comprising inner marginal beading b⁴ and outwardly and backwardly inclined faces b⁵.

A top ornament D surmounts the front plate B, being highest and pointed at the middle d, which is the apex of the shield-like scroll d', which is flanked by scrolls d², which curve downwardly from the lower portion of the shield-like scroll d' to higher corner-pieces d³ of fluted work. When the top piece is repeated by the grouping together of a plurality 40 of the front plates, the fluted corner-pieces d³ are brought together in pairs and form half-circle projections.

What I claim is—

The design for a front-plate head of a sirup- 45 tank for soda-water fountains, as shown and described.

HENRY J. WELSH.
